JOHN F. SLATER, OF GRINNELL, AND HENRY A. KLEIN, OF BELLEVUE, IOWA.

BOILER.

Application filed December 29, 1919. Serial No. 348,118.

Our invention relates to boilers, and has for an object to improve the construction and efficiency of this class of structures, and to provide a portable boiler, capable of use for generating steam for light engines, and especially for heating flats, dwellings, business places, or the like, either by steam or hot water.

Among the further objects of our invention are to provide a boiler in which the heated gases and products of combustion are brought into contact with a greater portion of the water carrying parts of the boiler, to more quickly heat the same; to provide an improved hopper and fire box construction below the magazine, and to regulate the entry and distribution of air to the fire to give a substantially perfect combustion and smoke consumption; to effect a material saving in fuel consumption, and make possible the efficient use of practically any grade of coal; the provision of a novel arrangement of water tubes to absorb the maximum amount of heat from the gases of combustion; to produce a more simple, economical and efficacious boiler, capable of use either for generating steam or heating water; and such further objects, advantages and capabilities as will later more fully appear.

Our invention further resides in the combination, construction and arrangement of parts illustrated in the accompanying drawings, and while we have shown therein a preferred embodiment, we desire it to be understood that the same is susceptible of modification and change, without departing from the spirit of our invention.

In the drawings:—

Fig. 1 is a vertical transverse section through a median plane of our improved boiler, a slight portion of the upper left hand corner being shown in elevation for the sake of clearness.

Fig. 2 is a fragmentary sectional view of the bottom portion of the boiler similar to Fig. 1, but taken on a median plane at substantially right angles to that of Fig. 1.

Fig. 3 is a horizontal transverse section through the boiler at an intermediate point.

Fig. 4 is a fragmentary horizontal transverse section, showing the arrangement of one of the air pipes for passage of air from the exterior to a point over the fire.

As will be seen from Fig. 1, our improved boiler comprises the outer water leg or shell, which is composed of the outer wall 1, and

the wall 2 concentric therewith, but spaced inwardly therefrom a suitable distance to provide the water receiving space 3. Concentric with the outer water leg, but spaced inwardly therefrom, is the inner water leg composed of the inner wall 4, and the wall 5 concentric therewith, but spaced outwardly therefrom a suitable distance to form the water receiving space 6.

Connecting and establishing communication between the outer water leg and the inner water leg, at the upper portion, are the tubes 7, and at the lower portion the water tubes 8. The tubes 7 will or will not be filled with water, depending on how high the water level is maintained in the boiler. If the boiler is used for steam purposes, it is obvious a suitable steam space will be left above the level of the water, while if the boiler is to be used for heating water, as will be the case when used in a hot water heating plant, the water would entirely fill the space between the various shells and in all of the tubes.

The space within the inner wall 4 forms a fuel magazine 9, provided at its upper end with the removable cover 10, for the introduction of fuel thereinto. In addition to tubes 7 and 8 there are other water tubes 11, extending radially from the inner water leg, and closed at their outer ends, as shown in Figs. 1, 2 and 3. The water in the tubes 11 is thus positioned to be quickly heated by the transfer of heat through the tubes 11, from the heated gases and products of combustion passing upwardly through the combustion chamber 12, which extends from the fire to substantially the top of the boiler, from which the combustion gases are led to the stack, through the pipe connection 13, in an obvious manner.

Attached to the boiler at a convenient point is the steam gauge 14, which may be of any type desired to suit the required conditions. When the boiler is used merely as a water heater, such steam gauge may, of course, be omitted. At the lower end of the outer water leg is the intake pipe 15, through which water may be supplied to the boiler, and at the upper end of the inner water leg is the outlet pipe 16 to conduct away the steam or hot water from the boiler, to the place of consumption. When the boiler is used in a hot water heating plant, the circulation of water will be outwardly from the boiler through outlet 16, through the various

radiators and other passages, and back through pipe 15, to the lower part of the boiler.

Below the lower end of the flue magazine 9, is the fire box 17, in which is provided the hopper 18, which may be built of fire brick or other suitable material, and the opposite faces 19 and 20 of which, as shown in Fig. 2, slope or incline inwardly and downwardly. The other remaining walls 21 and 22, as shown in Fig. 1, are substantially vertical. At the bottom of the hopper 18 is the grate 23, below which is the ash pit 24, provided with door 25. Through one of the walls of the hopper 18, is the passageway 26, opening into the hopper just above the grate 23, and provided with door 27. Above the passage 26, and approximately at the upper end of the hopper, is the opening 28, controlled by closure 29, which may obviously, if desired, be in the form of a door, or other suitable enclosure, capable of operation, to control the entry of air to the combustion chamber.

Passing through the walls 1 and 2 of the outer water leg, at a point near the top of the hopper, as shown in Fig. 2, is the air inlet pipe 30, which extends to a point well within the fire box and directly over the fire. Pipe 30 is provided at its outer end with the closure 31, which may be hinged or movably mounted in any suitable manner to permit its being opened or closed, to regulate the entry of air from without, through pipe 30, to a point directly over the fire. Any suitable number of these air pipes 30 may be provided, and the amount of air passing therethrough for discharge over the fire will be regulated by operation of closures 31, to permit more or less air to pass into the fire box, as desired. Doors 25, 27 and 29, and closure 31, may if desired, be provided with sliding grates, or of any other suitable construction to regulate the passage of air therethrough. The fire can be cleaned either through the grates or the space at the bottom of the hopper.

Referring to Figs. 1 and 3, it will be seen that in our improved form of boiler, the combustion gases will pass upwardly from the fire, through the combustion chamber, and around the water tubes, in such manner as to come in contact with the maximum amount of exposed water retaining surface, whereby to greatly increase the steaming or heating ability, to absorb the maximum amount of heat from the fire, and to greatly increase the economy of operation of the boiler. The fuel will feed downwardly in an obvious manner, into the hopper 18, and by suitable manipulation of doors 25, 27 and 29 and closure 31, we are enabled to secure within the fire box perfect combustion and smoke consumption.

We consider the air intake pipe 30 of great

importance, since through it air may be admitted to the fire at a point and in such quantities to give the proper mixture of oxygen with the combustion gases to produce perfect combustion. With this arrangement we are enabled to admit air to the fire, either from below the grate, above the grate at the bottom of the hopper, above the grate at the top of the hopper, or through the pipes 30 to a point directly over the fire, or any of the obvious combinations possible from such arrangement, as desired; thus adding greatly to the flexibility of the fire control, and enabling the operator to easily respond to any requirements of the fire to give perfect combustion.

Having now described our invention, we claim:

1. In a boiler, a vertically arranged cylindrical shell, a fuel magazine within said shell, a passage for heated gases around the magazine, a hopper below said magazine and having two of its sides partially downwardly and inwardly inclined, the other two sides of the hopper being vertically straight, a grate at the bottom of the hopper, an ash pit below said grate, adjustable means for admitting or excluding air below said grate, a lateral opening extending through the lower portion of the hopper and the shell just above the grate, adjustable means for admitting or excluding air to the interior of the bottom of the fire through said lateral opening, one or more openings through said shell at the upper level of the hopper to admit air just above the fuel bed, adjustable means for admitting or excluding air through said last mentioned openings, whereby any combination of admission or exclusion of air below the grate, above the grate at the bottom of the hopper, or above the hopper may be effected as desired.

2. A boiler of the character described comprising an outer fluid containing shell, a fuel magazine consisting of an inner fluid-containing shell enclosed within and concentric with said outer shell, means providing communication between said shells, a fire box enclosed by the outer shell and located below the lower end of the inner shell so that the products of combustion will pass upwardly through the space between the shells, a hopper in said fire box, means providing an outlet for said products of combustion, a grate in said fire box below said hopper, and means by which air may be selectively admitted through said outer shell into said fire box at a position above the grate and at the bottom of the hopper and at a position above the grate contiguous to the top of the hopper, and directly over the fire therein.

3. A boiler of the character described comprising an outer fluid-containing shell, a fuel magazine consisting of an inner shell enclosed within and concentric with said

outer shell, means providing communication within said shell, a fire box enclosed by the outer shell and located below the lower end of the inner shell so that the products of combustion will pass upwardly through the space between the shells, a hopper in said fire box, means providing an outlet for the products of combustion, a grate in said fire box below said hopper, said outer shell having openings positioned to introduce air into the fire box at positions contiguous to the

bottom and the top of the hopper respectively, means controlling admission of air through said openings, and an air inlet tube extending horizontally inward through the outer shell at a position approximately in line with the top of the hopper and directly above the fire. ¹⁶

In witness whereof, we hereunto subscribe our names to this specification.

JOHN F. SLATER.
HENRY A. KLEIN.
